Inventor

UNITED STATES PATENT OFFICE.

CLARK WILLIAM GEORGE, OF FAIRFIELD, IOWA.

VENDING MACHINE.

Application filed April 7, 1920. Serial No. 371,808.

To all whom it may concern:

Be it known that I, CLARK W. GEORGE, a citizen of the United States, and a resident of Fairfield, in the county of Jefferson and State of Iowa, have invented certain new and useful Improvements in Vending Machines; and I do hereby declare that the following is a full, clear, and exact description thereof, reference being had to the accompanying drawings, and to the letters of reference marked thereon, which form a part of this specification.

This invention relates to improvements in vending machines and consists of the matters hereinafter described and more particularly pointed out in the appended claims.

The object of the invention is to provide a coin controlled machine, which is of simple construction and which is efficient in operation, for vending packages of confections, such as chewing-gum, candy-mints, chocolate bars, and the like.

Another object of the invention is to so construct the machine that it will not deliver a package, when a coin other than that for which the machine is designed is used,—all washers, slugs, buttons, or other coin imitations used in an attempt to "beat" the machine, being inoperative. In the improved machine, the coin itself acts as the final delivery member or key required to make the package delivery mechanism operative, and all the traps provided for a spurious coin must be passed before it reaches the said key position.

Other novel features, as well as the several advantages of the invention, will be made more apparent as I proceed with my specification.

In the drawings:—

Fig. 1 is a longitudinal, vertical sectional view through a vending machine, embodying my invention.

Fig. 2 is a similar view through the bottom end of the vending machine, on an enlarged scale, with some of the parts in a position changed from that shown in Fig. 1.

Fig. 3 is a transverse vertical section through the machine in a plane indicated by the line 3—3 of Fig. 1.

Fig. 4 is a detail view, on an enlarged scale, of parts shown in the top end of Fig. 3 and which will be more particularly referred to later.

Fig. 5 is a horizontal section through the vending machine in a plane indicated by the line 5—5 of Fig. 1.

Fig. 6 is another horizontal section through the vending machine, in a plane indicated by the line 6—6 of Fig. 1.

Fig. 7 is still another horizontal section through the vending machine, in a plane indicated by the line 7—7 of Fig. 1.

Fig. 8 is a fragmentary plan view of a certain plate embodied in the vending machine and which will be more particularly referred to later.

Fig. 9 is a transverse, vertical detail section through the machine in a plane indicated by the line 9—9 of Fig. 2.

Fig. 10 is an enlarged detail view of parts shown in Fig. 9.

Fig. 11 is a longitudinal vertical section, on an enlarged scale, of parts shown in the top end of Fig. 1.

Fig. 12 is a side view of a modified form of vending machine embodying my invention.

Referring now in detail to that embodiment of the invention illustrated in Figs. 1 to 11 inclusive, of the accompanying drawings, 15 indicates a sheet metal, rectangular shell forming part of the casing for the vending machine, which is preferably of a height greater than its width or depth. Said shell is open at its rear and bottom ends and has upright side walls 16, an upright front wall 17 and a horizontal top wall 18. Said shell is secured at its open bottom end to a base-board 19, which in turn is secured to a metal base 20, the base and base-board providing the bottom of the casing. The open rear end of the casing is normally closed by a swinging door 21, which is hinged at one margin, as at 22, to one of the side walls 16, and carries on its other margin, a hinged hasp 23, which engages an eye 24 on the other side wall 16 and may be locked thereto by a lock 25 (see Fig. 7). The rear margins of the side walls 16 are bent inwardly toward each other to provide abutments against which the said door is closed.

Near the bottom of the casing, the side walls 16 are extended forwardly beyond the plane of the front wall 17. This forwardly extending part of the casing has a canopy top wall 26, which overhangs a curved apron

27, that extends upwardly and rearwardly from the front end of the base-board 19. Said apron receives a package when discharged in the operation of the machine, 5 and directs it toward a discharge mouth defined by the apron and the bottom edge of the canopy. The outer edge of the apron is curled upon itself or otherwise formed to provide a stop 27^a for the package discharged upon it.

10 In the front wall 17 of the casing, is an opening that is closed by a glass 28, through which the packages to be vended are visible to the purchaser for selection. 15 Said glass is secured in place in any convenient manner and its bottom edge projects a short distance below the rear top edge of the canopy 26.

10 Mounted on the inner surface of the door 21, is an upright coin chute member 29 that is spaced from and is secured to said door by top and bottom spacer blocks 30—31. Said coin chute member is preferably made from a block of wood having 25 a plurality of transversely spaced, vertical slits 32, which open through the ends and through the rear face of said block to provide a plurality of chutes or guideways for the coin to be used in operating the machine. The member 29 terminates at its top 30 a short distance from the top wall 18 of the casing, and terminates at its bottom in substantially the horizontal plane of the bottom edge of the glass 28. A sheet metal 35 plate 33 secured to the rear face of the member 29, closes the lower part of each coin chute slit 32, which is open at the back above said plate, for a purpose which will hereinafter be described.

40 In the bottom of the casing, a short distance below the bottom ends of the glass 28, and chute member 29, is located a pair of horizontally disposed, vertically spaced plates 34—35 (see Figs. 7 and 8). Said 45 plates are of an area approximating the horizontal area of the casing and their front ends extend into substantially the plane of the front wall 17, while their rear ends project rearwardly below the coin chute member 29, when the door 21 is closed. The top plate 34 provides a platform upon which rest the stack or stacks of packages to be vended. The bottom plate 35 (see Fig. 8) has a plurality of integral upright ears 36 50 at its corners, upon which the top plate 34 rests and by which it is secured in vertical spaced relation to said bottom plate. Through said ears extend upright bolts 37 which are secured in the base-board 19 and 55 act as supporting standards or posts for said plates 34—35.

60 Rising from the top plate or platform 34, are pairs of front and rear upright guide rods 38—39 arranged in vertical planes 65 intermediate the vertical planes of the

coin slots in the chute member 29, with a pair at each end beyond the outermost slot. Said rods are secured at their top ends to a horizontal shelf or tray 40, located above the top edge of the glass 28, 70 and extending rearwardly from the front wall 17. Said glass and the front surface of the chute member 29, together with the rods 38—39 before mentioned, provide a magazine for holding the packages to be 75 vended, in transversely spaced, vertical stacks, which rest upon the top plate or platform 34. On the top surface of the top plate 34, at its front end, are upright ribs 41 in line with each pair of rods 38—39, 80 and in the plane of the coin chutes 32 in the member 29, are provided longitudinal slots 42, extending substantially the full length of the platform plate 34. The rear ends of said slots terminate in a plane back of the 85 chutes 32 in the member 29 so that when a coin falls down through a chute 32, it will drop into an associated slot 42, as shown in Fig. 7. To guide a coin from a chute 32 edgewise into a slot 42, I provide 90 upon the rear end of the plate 34, upwardly and outwardly inclined ribs 43 as shown in Figs. 2—7 and 10. In the bottom plate 35, in the vertical plane of the slots 42, I provide narrower slots 44 on each side of which 95 are fixed ribs 45 that define coin runways. The slots 44 are narrower than the slots 42 so that when the proper coin is introduced into the machine and through the chutes 32 to said slots 42—44, said coin will 100 bridge the narrower slot 44. But if a coin or slug of proper diameter, but of less thickness passes through the chute 32 and slot 42, it will fall through the slot 44, as clearly shown in Fig. 10. The front end of 105 the bottom plate terminates back of the front end of the slots 42 so that when a package has been delivered from the machine through the use of the proper coin, said coin is deposited upon the base-board 110 19 at about the same time that the package is discharged upon the apron 27, as shown in Fig. 2.

46 indicates a bar which is located in the space between the plates 34, 35. Said bar 115 extends transversely of the coin-runway ribs 45, and is capable of a reciprocatory movement on said ribs. The bar 46 projects at its ends beyond the bottom plate 35, and its ends are engaged by spring arms 120 47 mounted on pins 48 on the base-board 19. Said spring arms act to hold the bar 46 normally in a position back of the rear ends of the coin runways and against stops 36, which in the example illustrated, are provided by the spacing sleeves between the rear end of the plates 34, 35 (see Fig. 8).

To the middle of the bar 46, which may be called a universal bar, is attached the rear end of a main actuating rod 49, the 130

front end of which projects through the canopy 26 where it is provided with a hand-grasp or knob 49^a. Said rod bears upon the top surface of the plate 35 which is cored 5 out between the ribs 45 for the sake of lightness.

At the front end of the platform 34 is located a swinging shelf 52. Said shelf is secured to a transverse horizontal rod 53 which has bearing at its ends in forwardly extending ears 54 on the bottom plate 35, as shown in Figs. 2 and 7. Said shelf has a slot 55 at its middle so that, when the universal bar 46 and the rod 49 are in their normal position, said shelf may straddle the rod and assume a substantially vertical position as shown in Fig. 1. While in this position, it acts as a guard against the insertion of a hooked wire or other implement, up through the delivery chamber for the purpose of withdrawing a package from the stack through the use of such implement. A spline 50 extending laterally from the rod 49, is adapted, when the rod is 25 moved forwardly, to engage a cam rib 52 on said shelf and swing the shelf to a horizontal position wherein it provides an extension of the top surface of the top plate or platform 34, to receive a package, when 30 delivered from the bottom of a stack and to prevent endwise tipping of the package before it is completely withdrawn from its stack. When the rod returns to its normal position, the shelf will fall by gravity and 35 discharge its package upon the apron 27. No matter what position said shelf is in, however, it prevents the insertion of an implement into the machine for the purpose of withdrawing a package.

To the top end of the front wall 17, is fixed a coin slot plate 60, having vertically disposed, horizontally spaced openings 61, through which the coins may be inserted. Said openings register with similar openings 62 in said front wall. 63, 64 indicate vertically spaced top and bottom plates which provide tracks or guides for the coins, from the plate 60 into the chutes 32 in the member 29. Said plates are preferably 45 slightly inclined downwardly and rearwardly as shown in Fig. 11, and have at their corners, engaging ears 65, through which rivets extend to secure them in the desired spaced relation.

The bottom plate 64 has depending ears 66 at its front end and similar ears 67 at its sides near its rear end, by means of which both plates are secured in position in the casing. On the opposed surfaces of said plates, are provided laterally spaced, longitudinally curved ribs 68-69 respectively, arranged in pairs. The ribs 68 of each pair of ribs, on the top plate 63 define a guide or track for the top edge of a coin while the associated ribs 69 on the bottom plate de-

fine a guide or track for the bottom edge of a coin. Said tracks or guides of course, although being curved laterally, begin in line at their front ends with the openings 61-62 and open into the top ends of an associated 70 coin chute 32 in the member 29. Preferably, the ribs 68-69 are slightly offset laterally with respect to each other, as shown in Fig. 4, so that the coin assumes an inclined position. With the tracks curved in 75 this manner, a coin of smaller diameter than that of the coin designed to operate the machine, cannot be made to follow the track, by being held at the inlet slot 61, and then given a quick impulse or movement by 80 flicking the coin with the finger.

Both plates 63-64 are provided with openings 63^a-64^a for the purpose of lightening said plates. The openings 64^a in the bottom plate also serve another purpose in 85 this manner. Supposing a coin or slug of a smaller diameter is carefully inserted through the slots 61-62. Said coin will not engage between the ribs on the top plate and as it is thus unsupported or unguided 90 at its top edge, it will fall laterally upon the adjacent pair of ribs and therefore fall through one of the openings 64^a between the ribs 69 to be deposited upon the tray 40. At the rear edge of the bottom plate 64, between the ribs 69 of each pair, I provide a small, thin sharp blade 70, which slightly overhangs the associated chute 32. This blade will cut any string or thread to which 95 has been attached a proper coin for withdrawing it after it has operated the machine. 100

To prevent the use of a slug of the proper diameter and weight, but containing spurious metal capable of being influenced by a 105 magnet, I provide a pair of horseshoe magnets 72 which are mounted in place between the member 29 and door 21, just below the spacing block 30. There is one magnet for each pair of coin chutes 32, the arms of each 110 magnet being arranged so as to bridge the top end of the associated coin chute 32. Such a slug after entering the top end of the chute 32, will be attracted by the magnet and will be withdrawn or pulled from 115 the chute to roll on the front side of the magnet and be deposited either on the top of the spacing block 31, or on the base-board 19. If a paper or fiber slug is used, it will drop down the coin chute and strike against 120 a light leaf spring 73 which will deflect its coarse out of the chute 32, through an opening in the plate 33. A spring 73 is associated with each chute. While said spring will deflect a light weight slug, it will readily yield through holes 73^a in line with the chute, to permit the passage of a coin of proper weight.

In Fig. 12, I have shown a modified form of the machine, in which a rocking lever is 130

employed to actuate the machine after deposit of the proper coin, instead of the rod 48 before mentioned. In this instance, 75 indicates a lever fixed to the projecting end of a 5 rock shaft 76, which extends through one side wall of the machine. The lever is limited in its movements by stops 77, on the casing side wall. The end of the rock shaft 76 within the casing is connected in any suitable manner to the universal bar 46, so as to 10 translate the rocking movement of the shaft 76 into a reciprocating movement of the universal bar 46.

The operation of my improved vending 15 machine is as follows: Assume that a coin of the proper denomination, say for instance, a five cent piece, or "nickel," is inserted edgewise through one slot 61 in the coin plate 60. Said coin will pass through 20 the associated slot 62 and then roll on its edge rearwardly on the inclined curved track provided by ribs 68-69 on the plates 63-64. Said coin will strike the top spacer block 30, and will be deflected downwardly 25 in an edgewise manner, through the associated coin chute 32 in the member 29. As said coin is not influence by the magnets, it will pass by them. As it engages a leaf spring 73, its weight will swing the same 30 into the slot 73^a and pass by said spring which will immediately return to its normal position.

Said coin, when passing out through the chute 32 is directed by the ribs 43, into and 35 through the rear end of the slot 42 into position in front of the universal bar 46, the edge of said coin bridging the narrower slot 44 in the bottom plate 35, so as to be capable of being rolled on its edge in 40 the runway provided by the ribs 45 thereon. The body of the coin will engage within the slot 42, so as to be held in edgewise position, and the top of the coin will project above the top plate 34 into a position to engage the bottom package of the stack on the 45 platform. The rod 49 is then pulled outwardly to move the universal bar 46 forwardly, with its front edge engaging the rear edge of the coin, and the coin, acting 50 as a key to connect the bar to the package, will push the package forwardly to deliver it into the space below the canopy 26. At the same time, the spline 50 on the rod 49 will engage the cam rib 51 on the shelf 52 55 and swing it into a horizontal position flush with the top surface of the top plate 34, ready to receive said package. Thus the coin acts to impart the movement of the universal bar to the package which is delivered 60 upon the horizontal shelf 52.

When a package is removed from the bottom of a stack, the next succeeding package will assume, by gravity induced by itself and the packages above it, a position 65 on the top plate formerly occupied by the

package discharged, so as to be in proper position for the next operation. It is to be noted that the bottom edge of the glass 28 engages the end of the second package of a stack and thus prevents the discharge of more 70 than one package at an operation.

Just as a package is delivered upon the shelf 52, the coin rolls off the front end of the bottom plate, as shown in Fig. 2, and is deposited upon the base board 19. If desired, a tray may be placed upon said base-board to catch the coins. The rod 49, the outer movement of which has been arrested by the engagement of the spline 50 with the depending part of the canopy 26 is now 80 released and the spring arms 47 move the universal bar and said rod to their normal, initial positions. As the rod moves inwardly, the shelf 52, no longer supported by the spline 50, swings downwardly and the package 85 slides off the shelf and falls upon the apron 27, from which it may be withdrawn from the machine. The machine is now ready for the next operation.

As is apparent, a coin may be inserted in 90 either or all of the coin chutes and upon operation of the rod 49, a package will be discharged for each coin thus inserted. Supposing in trying to "beat" the machine, two coins of proper denomination are 95 inserted into the same inlet slot 61, one right after the other. The said coins will drop down the chute 32 and one will rest on the bottom plate 35, and the other will rest upon the first and extend part way into the 100 bottom end of the chute. Upon actuation of the rod 49, the bottom coin will act as a key to transmit the movement of the bar 46 to a package to discharge it, while the second coin will fall into the place formerly occupied by the first coin. When the universal bar moves back to its normal position, its rear edge, which is beveled as indicated at 46^a, will act to lift the coin to 105 permit said bar to pass, whereupon the coin 110 will assume a position in front of said bar. Upon a second actuation of the rod 49, a second package will be discharged by means of this coin. Thus a package will be discharged for each coin but no more. 115

When one stack of the packages has been exhausted, this is made apparent to the purchaser, from a view through the glass in the front wall.

It will be manifest that the characteristics of a proper coin, such as diameter, thickness, weight and kind of material, have all been taken into consideration in providing the traps heretofore described. The machine will thus operate only when a proper 125 coin is inserted, and will trap, but not return slugs and the like.

The machine is easily loaded with packages by opening the door 21, and placing the packages in stacks between the guide 130

rods. The machine is water-proof, is simple and efficient in operation, and will not get out of order.

While in describing my invention, I have referred to certain details of mechanical construction and arrangement of parts, I do not wish to limit myself thereto except as pointed out in the appended claim.

I claim as my invention:—

10 In a vending machine, the combination of a casing having a front wall discharge opening and a rear door, a platform for supporting vertical stacks of packages, a coin controlled discharge mechanism mounted on

15 said platform, rods rising from said plat-

form and spacing said stacks from each other, and a member on said rear door having a plurality of chutes for directing coins into said discharge mechanism, said platform, front wall, coin chute member and 20 rods providing a magazine for holding said vertical stacks of packages.

In testimony that I claim the foregoing as my invention, I affix my signature in the presence of two witnesses, this third day of 25 April, A. D., 1920.

CLARK WILLIAM GEORGE.

Witnesses:
